UNITED STATES PATENT OFFICE

2,646,214

MAILBOX INCLUDING SPRING URGED DOOR

Frank M. Cuplin, Crowley, La.

Application April 27, 1951, Serial No. 223,233

6 Claims. (Cl. 232—45)

1

This invention relates to new and useful improvements in mail boxes and the primary object of the present invention is to provide a mail box including a vertically swingable door that is spring urged to its closed position when released from its open position.

Another important object of the present invention is to provide a mail box in which the spring urging the door to its closed position is concealed and shielded beneath the bottom wall of the mail box.

A further object of the present invention is to provide a mail box having a closure with a sealing flange that will overlap the body of the box at one end to shield articles placed in the box against rain, snow or the like.

A still further aim of the present invention is to provide a mail box of the aforementioned character that is free of sharp edges and which is simple and practical in structure, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary perspective view of the present invention;

Figure 2 is a vertical sectional view taken substantially on the plane of section line 2—2 of Figure 1;

Figure 3 is a horizontal sectional view taken substantially on the plane of section line 3—3 of Figure 1;

Figure 4 is a bottom plan view of Figure 1; and,

Figure 5 is a fragmentary front elevational view of Figure 1 showing the closure in its open position and the manner in which the closure is retained in its open position.

Referring now to the drawings in detail, wherein for the purpose of illustration, there is disclosed a preferred embodiment of the present invention, the numeral 10 represents the mail box including a casing 12 whose side walls are secured by rivets or the like to the depending side flanges 14 of a bottom wall 16.

The casing 12 is formed with a forward open-arch end one-half of the forward edge of which is turned inwardly to form a flange 18. The other half of the forward edge of the open end is rolled inwardly upon itself to form a beading 20.

The mail box is provided with a door or closure 22 whose lower left hand corner is secured to the forward flange 24 of the bottom wall 16 by a hori-

2

zontal pivot 26 to permit vertical swinging movement of the door to its open and closed position. The door 22 is formed with a sealing flange 28 that will overlap the forward end of the casing 10 when the door is in its closed position with its unflanged portion disposed behind and under the flange 18.

Means is provided for urging the door to its closed position. This means comprises a coil spring 30 whose forward hook end 32 extends through an aperture in the door adjacent the pivot 26. The rear hook end 34 of the spring 30 extends through registering apertures in one side flange 14 of the bottom wall 16 and one side wall 15 of the casing 10. The spring 30 is disposed beneath the bottom wall 16 and extends across one corner of the bottom wall 16 to be expanded or extended as the door 22 is swung downwardly to its open position.

A resilient holding tongue 36 is struck from the flange 24 remote from the pivot 26. The door 22 will engage under this tongue 36 to be retained in its open position until the door is manually moved over the tongue whereupon the spring 30 will urge the door to its closed position.

The upper portion of the casing 12 supports a forwardly extending L-shaped spring member 38 having a channel 40 that will receive the rib 42 on the web of a U-shaped member 44 secured to the door 22 to yieldingly retain the door in its closed position.

A compressible spacer or washer 46 is disposed on the pivot 26 between the door 22 and flange 24 and permits sufficient play in the door for the door to engage under the tongue 36 and the flange 28 to clear the corner of the casing.

Having described the invention, what is claimed as new is:

1. A mail box comprising an elongated horizontally disposed casing having a forward open end and a bottom wall, a door having a lower corner pivoted to the bottom wall for vertical swinging movement in a plane perpendicular to the horizontal axis of the casing toward and away from the open end of the casing to selectively cover and uncover the opening, a spring connecting the door to the bottom wall and yieldingly retaining the door against the open end of said casing, interconnecting means between the door and the casing for holding the door in its closed position, and a holding tongue on the bottom wall at the open end of the casing for engaging and holding the door in its open position.
2. A mail box comprising an elongated horizontally disposed casing having a forward open end and a bottom wall, a door for the open end of

the casing, a single horizontal pivot disposed longitudinally of the casing and securing the door to the bottom wall, and an elongated spring underlying the bottom wall and attached at one end to the bottom wall and extending toward the door adjacent the pivot, the other end of said spring being secured to the door adjacent the pivot, said spring being expanded as the door is moved to its open position about the pivot.

3. A mail box comprising a horizontally disposed casing having a forward open end, a door for the open end of the casing having a lower corner, a horizontal pivot securing the lower corner of said door to said casing, and an elongated spring having a forward end attached adjacent 15 the lower corner of the door and a rear end secured to the casing and inclined relative to the door, said spring being expanded as the door is moved about its pivot to an open position.

4. A mail box comprising a casing having an 20 elongated bottom wall including a depending flange, said casing having an open forward end, a door for the open end of the casing including a lower corner, a horizontal pivot securing the lower corner of the door to the flange at the forward 25 end of the casing, an elongated horizontally disposed spring disposed diagonally across one corner of the bottom wall and located below the bottom wall, said spring having a forward end attached to the door adjacent the pivot, and said 30 spring having a rear end attached to said flange,

said spring being extended as the door is moved about its pivot to an open position.

5. The combination of claim 4 and a sealing flange on said door overlapping the forward end of the casing when the door is in its closed position.

6. A mail box comprising a casing having a forward open end and a bottom wall including a depending flange at the open end of the casing and extending transversely of the casing, a door for the open end of the casing and including a lower corner and a sealing flange, a horizontal pivot securing the lower corner of the door to one end of the depending flange, a tongue struck outwardly and forwardly from the depending flange at the end thereof remote from the pivot for engaging the door to retain the latter in its open position, and a spring underlying the bottom wall and terminally secured to the bottom wall and the door for yieldingly urging the door to its closed position with the sealing flange overlapping the open end of the casing.

FRANK M. CUPLIN.
